To all whom it may concern:

Be it known that I, Leslie C. Peltier, a citizen of the United States, residing at Delphos, in the county of Allen and State of Ohio, have invented a new, original, and ornamental Design for a Child's Rocking Chair or Similar Article, of which the following is a specification, reference being had to the accompanying drawings, forming a part thereof.

Fig. 1 is a side elevational view of a child's rock-ing chair or similar article, showing my new design;

Fig. 2 is a top plan view; and

Fig. 3 is a perspective view thereof.

I claim:

The ornamental design for a child's rocking
chair or similar article, substantially as shown.

LESLIE C. PELTIER.
